(57) **CLAIM**

The ornamental design for a container for use by the visually impaired, as shown and described.

DESCRIPTION

FIG. 1 is a perspective view of a container for use by the visually impaired;

FIG. 2 is a front view thereof;

FIG. 3 is a right-side view thereof;

FIG. 4 is a back view thereof;

FIG. 5 is a left-side view thereof;

FIG. 6 is a top view thereof; and,

FIG. 7 is a bottom view thereof.

The evenly broken lines in the drawings depict portions of the container for use by the visually impaired that form no part of the claimed design. The dash-dot broken lines in the drawings define the boundaries of the claimed design and form no part of the claimed design.

1 Claim, 6 Drawing Sheets
